ELECTRIC TABLE LIGHTER

Samuel F. Speers, East Providence, R.I., assignor to
Evans Case Co., a corporation of Massachusetts

Application June 25, 1958, Serial No. 51,528

Term of patent 14 years

(Cl. D48—27)

Fig. 1.

Fig. 2.

Fig. 1 is a top plan view of an electric table lighter showing my new design; and

Fig. 2 is a side elevational view thereof.

Fig. 3 is a partial sectional view of the top portion of the lighter taken substantially on line 3—3 of Fig. 1.

The side of the lighter not shown is the same as the side shown. The horizontal lining shown in Fig. 2 indicates surface ornamentation in the form of striations.

I claim:

The ornamental design for an electric table lighter, substantially as shown and described.
